APPARATUS FOR SUBDIVIDING BLOCKS
OF ICEMiguel J. Uline, Washington, D. C., assignor to The
RFC Mortgage Company, Richmond, Va., a cor-
poration of Maryland

Application December 1, 1938, Serial No. 243,453

6 Claims. (Cl. 62—112)

My invention relates to machines for cutting a block of ice into cubes, more particularly those wherein a flow of fluid through thin tubes furnishes heat to the tubes causing them to pass through a block of ice pressing against it. By this invention I am able to divide evenly and accurately a block of ice along planes parallel to one of its sides and then along planes perpendicular to the planes just mentioned and to each other.

Past efforts towards securing ice cubes of uniform dimensions from a block of ice, where the weight of the ice block itself generated the pressure necessary for division through melting contact, have encountered the difficulty of an uneven division non-parallel to the sides of the original ice cake. The heated edges used for separation have exhibited in the past an uneven transfer of heat units. Sometimes the construction was such that some corner or edge of the block of ice would catch on gratings formed of the heated severing tubes. Also temporary flexible fluid connections from the severing box to a source of heating fluid have tended to give trouble by breaking or leaking.

An object of my invention is to overcome the above difficulties.

Another object of my invention is to provide an apparatus for severing a block of ice into cubes by first causing the ice in the primary cut to slide of its own weight downward past heated edges to produce a plurality of severed layers of ice, then to tilt the containing member approximately 90 degrees and cause these severed layers lying one above the other to go downward of their own weight in the secondary cut past heated edges in the two planes perpendicular to the sides of the original block and perpendicular to the planes dividing the layers.

A further object of my invention is to provide a tripping means for causing the mass of ice to be turned approximately 90 degrees when the primary severing has been completed, such tripping means having an element constantly urged downwardly against the ice block so as to release the tripping means when the ice block has passed through the heated edges that provide the primary severing.

Yet another object of my invention is to provide a means for constantly pressing downward against the ice block during the primary severing operation, such pressure being applied above the colder side of the primary severing edges, thereby tending to equalize the speed of severing between each end of the primary severing tubes.

Still another object of my invention is to provide a means of insuring that the mass of ice to be severed will slide downward with a slight pressure at one side against a smooth guiding surface, both in the primary severing along a

single set of parallel planes and in the final severing along two sets of parallel planes perpendicular to each other and to the original cutting planes.

Yet another object of my invention is to provide a means of furnishing a continuous supply of fluid for furnishing heat units to the cutting edges without the necessity of temporary or pliable connections to the movable ice containing means.

A still further object of my invention is to provide a means for readily changing the downward pressing member, which is used to press against the ice block, from operating position to an inoperative position and means for retaining it in inoperative position so that a fresh block of ice may be placed in position for severing, without the necessity of manually holding the downward pressing member out of the way.

With these and other objects in view, which may be incident to my improvements and which may appear from my disclosure thereof, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood I have shown in the accompanying drawings means for carrying the same into practical effect without limiting the improvements in their useful applications to the particular constructions, which for the purpose of explanation have been made the subject of illustration.

Figure 1 represents a side elevation view of my invention.

Figure 2 is a front elevation view of my invention.

Figure 3 is a plan view showing in dot and dash lines the direction to which the ice contacting arm of the tripping bar may be swung.

Figure 4 is a side elevation view broken away to expose the ice severing box and further broken away in the upper and left hand portions to expose section of Figure 2, with dot and dash lines indicating the overturned position of the ice severing box.

Figure 5 is an enlarged sectional view taken along the line 5—5 of Figure 3, looking in the direction of the arrows.

Figure 6 is an enlarged sectional view taken along the line 6—6 of Figure 5 looking in the direction of the arrows.

Figure 7 is an enlarged sectional view taken along the line 7—7 of Figure 4 looking in the direction of the arrows.

Figure 8 is an enlarged sectional view taken

along the line 8-8 of Figure 1 looking in the direction of the arrows.

Figure 9 is a perspective view of my fluid circulation system showing the directions of flow, such view being partially broken away and in section to show the blocking of certain passages.

Referring to the Figures 1 and 2 of the drawings, I utilize a supporting frame 1 formed of legs 2, 2', 3 and 3' having journal bearings shown generally as 4 and 4' placed at its apex. Fitted in each of these bearings 4 and 4' are trunnions 5 and 5', respectively. These trunnions are bolted to an ice severing box designated generally as 6, at points sufficiently below and to the rear of the center of gravity possessed by severing box 6 so that this severing box is constantly urged, both when empty and when filled with ice, toward the overturned position shown by the dot dash lines of Figure 4.

Referring to Figures 1, 3 and 4, the ice severing box 6 comprises a back wall 7, sidewalls 8 and 8', a bottom 9, top grating indicated generally as 10 and a front grating indicated generally as 11. These gratings 10 and 11 are secured, preferably by bolting, to the sidewalls 8 and 8' by clamps 12. The front grating 11 is also secured to the bottom 9 by clamps 12. The back wall 7 has a central upwardly disposed extension 13 terminating in an outwardly bent portion 13'.

As shown in Figures 1 and 2, lugs 14 and 14' are attached to sidewalls 8 and 8', respectively, and extend out from these sidewalls to contact legs 2 and 3 upon sufficient forward tilting of the severing box 6. Contact position is shown by the dot dash lines of Figure 4. Another pair of lugs 15 and 15', attached to sidewalls 8 and 8', respectively, extend out from these sidewalls to contact legs 2' and 3' upon sufficient tilting back of the severing box, as shown in the upright position of Figure 1.

Resisting the forward tilting force of the severing box 6 to hold it in its upright position is a latch 16 pivotally mounted on a pin 17, attached to the rear leg 3'. The latch 16 has formed at its opposite end a counter-balance 18. Latching point 19 engages dog 20, which is suitably joined to the severing box 6 at its lower rear corner adjacent the latch 16.

A socket 21 which carries a sliding rod 22 is attached by clamps 23 and 24 to the rear wall of the severing box 6 on the side next to the dog 20. The socket 21 is positioned perpendicular to the axis of rotation of the ice severing box and clears the rear wall extension 13. The sliding rod 22 has an upper portion in the form of an arm 25 extending approximately at right angles to the direction of sliding in the socket 21. Arm 25 is adapted to apply an even pressure to the top side of a cake of ice on the end adjacent the side wall 8'. Hooks 26 and 27 attached respectively to the sliding rod 22 and the socket 21 are urged relatively toward one another by a spring 28, thus causing the arm 25 to exert a downward pressure upon, and follow the top surface of the ice cake. Riding in a vertical slot 29 of the socket 21 is a latch trip member 30 joined to the sliding rod 22 and extending out therefrom to the plane of pivoting of the latch 16. When the ice has been completely severed along the primary lines of cutting and the sliding rod 22 with its arm 25 has been urged downward in the socket 21, the trip member 30 will force downward the latching point 19 of the latch 16, thus releasing the dog 20 and allowing the severing box 6 to swing into the position indicated by the dot dash lines of Figure 4.

Referring to Figure 3 it will be seen that the arm 25 may pivot approximately 90° around to the dot dash position shown as 25', thus allowing a cake of ice to be placed in position, and the arm 25 swung back over the top surface of the cake. As shown in Figure 4, the slot 29 has at its upper extremity a lateral extension 31 to receive the trip member 30 as the sliding bar 22 twists to allow the arm 25 to be swung to its out-of-the-way position 25'.

As shown in Figures 1, 2, and 9, the piping system comprises in part an inlet pipe 31 carrying water or other heating fluid from a pressure source, not shown, connected through an elbow 32 into an axis pipe 33. The axis pipe 33 passes through the packing ring 34 which is free to rotate around it. The trunnion 5 has loosely threaded into it, the axis pipe 33, leaving the trunnion 5 free to rotate. A sidewall pipe 35, placed in oblique relationship to the bottom 9 and back 7, joins the trunnion 5 through a multiple elbow 36 with the top grating 10 and the front grating 11.

On the outlet side, a multiple elbow 36' connects the gratings 10 and 11 with a sidewall pipe 35', the trunnion 5', a packing ring 34', an axis pipe 33', an elbow 32', a vertical exit pipe 31', an elbow 37, and a floor pipe 38. The piping connections on the inlet side are made in the same way as those on the outlet side indicated by a corresponding primed numeral.

Referring to Figure 9, the system of severing tubes embodied in the top grating 10 and the front grating 11 comprises three supply mains 39, 40 and 41 and three exhaust mains 42, 43, and 44 between which three sets of parallel severing tubes 45, 46, and 47 carry the heating fluid.

Supply main 39 threads into multiple elbow 36 and is blocked on the other end by cap 48. Supply main 40 structurally connects multiple elbows 36 and 36', but direct fluid passageway between main 40 and elbow 36' is blocked by plug 49. Supply main 41 structurally connects multiple elbow 36 through elbow 50 with exhaust main 43, but direct fluid passageway between main 41 and elbow 50 is blocked by plug 51.

Exhaust main 42 threads into multiple elbow 36' and is blocked at the other end by cap 52. Exhaust main 43, threaded into elbow 50, is connected through an elbow 53 with exhaust main 44 which is connected with multiple elbow 36'.

Severing tubes 45 afford a passageway for heating liquid between the mains 39 and 42. Severing tubes 46 afford a passageway for heating liquid between mains 40 and 43. Severing tubes 47 afford a passageway for heating liquid between mains 41 and 44.

Referring to Figure 5, the supply main 39 clamped to the sidewall 8 by the clamp 12 is suitably joined as by soldering to the tubes 45 to form a passageway for heating liquid. Also, the supply main 39 is shown welded or soldered to the end 54 of the clamp 12. The tubes 45 have rounded ends 55, as best shown in Figure 6, adapted to fit within a round hole in the supply main 39.

Referring to Figure 6, bracing strips 56 are positioned below the tubes 45. These bracing strips 56 are suitably joined, as by soldering, at their upper edges with the lower edges of tubes 45, thereby enabling the tubes 45 to carry the weight of an entire block of ice without bending.

Referring to Figure 7, the tube 47 is joined at its rounded end 57 with the supply main 41. The tube 47 has an angularly disposed portion 58 ad-

jacent the rounded end 57, enabling the tube 41 to be offset and lie adjacent to and outside of the outside edges of the tube 46. In the preferred form of my invention there is contact between the edges of tubes 46 and 47, enabling the front grating 11 formed by tubes 46 and 47 to withstand better the weight of layers of ice in the severing box 6 after it has been tripped into its overturned position. Due to the fact of this braced construction in the front grating 11, my preferred form does not include bracing strips, such as strips 56.

Referring to Figure 8, the trunnion 5', suitably joined at its base 59 to sidewall 8', carries a bearing sleeve 60 journaled in journal bearing 4'. An extension 61 of the trunnion 5' adjacent its base 59 carries a passageway 62 which makes a ninety degree connection with an axial passageway 63. The base passageway 62 receives the threaded sidewall pipe 35.

The axial passageway 63 has a threaded end 64 extending back for a greater distance from the opening than is usual with tightly fitting screw thread joints. The threaded end 64 receives, without binding, a proportionately long, threaded end 65 of the axial pipe 33'. The exhaust pipe 31' is connected to the axial pipe 33' through elbow 32 as has already been explained.

Screwed on to an axial projection 66 of the trunnion 5', and surrounding a portion of the axial pipe 33' is the packing ring 34'. Between these parts 33', 34' and 66 is held packing material 67 to prevent any leaking out of heating fluid from the piping system.

The trunnion assembly just described for the outlet side of the severing box 6 is duplicated by corresponding parts on the inlet side. The same provision for a rotatable connection is embodied in the trunnion assembly formed with trunnion 5.

The method of operating my ice cubing machine is to institute a flow of water or other heating medium through the piping system as shown in Figure 9 by the arrows. This is done by connecting a source of supply to the inlet connecting pipe 5 and disposing of the exhaust heating medium through the outlet floor pipe 14. The heating medium may be hot water, steam, water at room temperature, or other readily available fluids for delivering heat units to the severing tubes.

In operating my invention, the severing box 6 is placed in the upright position shown in Figure 1 and the latch 16 is allowed to engage the dog 20. The sliding rod 22 is at the same time lifted so that the trip member 30 is raised above tripping position to the greatest height permitted by the slot 29. While the sliding rod 22 is at its highest position it is twisted in the direction of the lateral slot 31 by the leverage of arm 25 until arm 25 assumes the position indicated by 25'. The trip member 30 moves into the far end of the slot 31, being held there by friction or alternatively by a slightly lowered position of the far end of lateral slot 31.

While the arm 25 is thus held without manual attention and while the trip member 30 is thus held up out of position for tripping the latch 16, the block of ice to be cut into cubes is then placed upon the grating 10. The block of ice is preferably of dimensions approximating the inside dimensions of the severing box 6. After the block of ice is placed on the grating 10, the arm 25 is swung back over the ice from the dot dash line position of Figure 3 to the solid line position shown in Figure 3. The arm 25 is therefore urged

downwardly against the outlet pipe end of the ice block, by the tension of spring 28.

At the start of the cutting process it will be seen that the ice block is supported by the grating 10 which forms a supporting plane inclined downwardly toward the back wall 7 and its backing plate extension 13. The extension 13 carries a portion of the weight of the ice block and its smooth walls serve to guide the downward progress of the ice block as it is severed.

Due to the absorption of heat in the melting process incident to the primary severance of the ice block by the cutting tubes 45 of the top grating 10, the temperature of the severing tubes 45 will progressively diminish from the inlet ends toward the outlet ends. To overcome this tendency towards uneven rates of cutting the pressure of the arm 25 urged by the spring 28 is placed downward upon the end of the block resting on the colder ends of the cutting tubes 45. Therefore, due to the more efficient transmission of heat from the colder ends of the cutting tubes 45 caused by the firmer contact, I am able to secure an even rate of severance at both ends of the ice block along the planes of cutting.

When the ice block has been completely severed into slabs corresponding to the planes of division of the tubes 45 it is apparent that the arm 25 will be permitted to pass downward to the full distance necessary to enable the tripping member 30 to release the latch 16. At this point the center of gravity forward of its axis will cause the severing box 6 to tilt forwardly to the overturned position shown by the dot dash lines of Figure 4. In this new position the mass of ice will be forced against the tubes 46 and also after a short cutting process against the tubes 47.

In order to insure that the slabs of ice are guided properly during the secondary cut, the stop 15 is so positioned that the smooth bottom wall 9 does not quite attain a true vertical position. On the contrary, there is a slight but constant pressure against the bottom wall 9 which guides the slabs of ice during the secondary cutting process. As each slab of ice completes its passage through the grid formed by tubes 46 and 47, small cubes are formed which fall into any suitable container placed below the severing box 6.

During both primary and secondary cutting processes, the smooth sidewalls 8 and 8' act upon a mass of ice fitting snugly between them, to assist in keeping the ice mass level as between the inlet and outlet sides. This guiding force augments that of the arm 25, during the primary cut.

It will be seen from the above description of my invention and its mode of operation that I have produced a machine operable to divide a cake of ice vertically into flat slabs of uniform dimensions. This is largely insured by the guiding action of the smooth back wall sloping downward toward the front of the severing box.

Also contributing to this result is an even speed of severing over the area defined by the primary severing tubes. The ends of these tubes nearest the exhaust mains and which are therefore cooled to a lower temperature by the melting of the ice have a greater pressure of ice against them due to the following arm.

Because of the large inner cross-section of the mains as compared to the tubes, each tube receives practically the same flow of heating liquid through it. Hence, the rate of cutting is approximately the same from one end of each tube

to the other and also as between the several primary severing tubes, causing the block of ice to retain its original angular relationship with the severing box as it passes through the top of such box.

Also, when the ice block fits snugly between the two side walls, proper alignment with the severing edges is favored. This aids alignment of the secondary cutting operation as well as the primary cutting operation.

During the secondary severing operation, the ice slabs slide downward with sufficient pressure against the upturned bottom of the severing box to maintain their straight path through the gridiron formed by the secondary severing tubes.

As was already mentioned, the sidewalls assist in guiding the secondary cut. If the ice mass fitted snugly against the side walls during the primary cut, it would continue to do so during the secondary cut; it would continue to do so during the secondary cut, because the portions melted away during the primary cut only affected the dimensions of the ice mass from front side to back wall of the box. Furthermore, any twisting or side sway of the ice in the secondary severing would have less effect on the even and uniform appearance of the ice cubes in the cutting sequence employed than would be the case if the mass were cut into long square rods and then cut into cubes. In the latter named sequence, the ice rods could fall without guiding action from the side walls into position for oblique secondary cutting.

By having conduits through the trunnions for carrying the heating fluid to and from the severing box, I am able to dispense with temporary pliable connections for this purpose.

Finally, by having separate sets of supply and exhaust mains for the primary and the secondary severing tubes, and by connecting the primary severing tubes in shunt flow with the secondary severing tubes, my construction allows a faster and more uniform cut, than with the primary and secondary severing tubes in series.

While, for purposes of illustration, I have shown one form of construction of my ice cubing machine, it is obvious that various changes may be made in the construction without departing from the spirit of my invention.

For the above reasons I wish it understood that it is my intent to be only limited by the prior art and the scope of the appended claims.

1. An ice cubing machine of the cleaving-by-melting type, comprising in primary position two flat parallel side walls, a flat rear wall, a flat bottom, said rear wall and said bottom having means joining said side walls and positioned at right angles to the side walls and to each other, primary cleaving edges carried by the side walls fixedly above and parallel to the bottom, secondary cleaving edges carried by the side walls fixedly in front of and parallel to the rear wall, the side walls and rear wall and bottom and cleaving edges forming a tilt carriage, an auxiliary back guide carried by the tilt carriage, said back guide being positioned above the rear wall and substantially in the same plane as the rear wall whereby a block of ice may rest against the back guide while being supported upon the primary cleaving edges, a supporting frame for the tilt carriage, said tilt carriage being rotatively supported by the supporting frame so that the side walls remain perpendicular to the axis of rotation, means carried by the tilt carriage and the supporting frame to releasably hold the tilt car-

riage in the above described primary position wherein the rear wall is predominately vertical and wherein the rear wall and the bottom form a dihedral angle the two planes of which converge downwardly toward the apex, said axis of rotation of the tilt carriage being so positioned that the tilt carriage is normally overbalanced and urged into secondary position, said secondary position being that position wherein the bottom is predominately vertical and the rear wall is predominately horizontal, and means to prevent the tilt carriage from rotating past said secondary position upon release of said holding means.

2. An ice cubing machine of the cleaving-by-melting type comprising in primary position two flat parallel side walls, a flat rear wall, a flat bottom, said rear wall and said bottom extending between said side walls and positioned at right angles to the side walls and to each other, primary cleaving edges spaced fixedly above and parallel to the bottom, secondary cleaving edges spaced fixedly in front of and parallel to the rear wall, the side walls and rear wall and bottom and cleaving edges forming a tilt carriage, an auxiliary back guide carried by the tilt carriage, said back guide being positioned above the rear wall and substantially in the same plane as the rear wall, whereby a block of ice may rest against the back guide while being supported upon the primary cleaving edges, a supporting frame for the tilt carriage, said tilt carriage being rotatively supported by the supporting frame so that the side walls are perpendicular to the axis of rotation, means carried by the tilt carriage and the supporting frame to releasably hold the tilt carriage in the above described primary position wherein the rear wall is predominately vertical and wherein the rear wall and the bottom form a dihedral angle the two planes of which converge downwardly toward the apex, means to hold the tilt carriage in secondary position, said secondary position being that position wherein the bottom is predominately vertical and the rear wall is predominately horizontal.

3. In an ice cubing machine of the cleaving-by-melting type, a tilt carriage having cleaving edges spaced to mark out two planes substantially perpendicular to one another and thereby forming a primary grating and a secondary grating, means for heating said gratings, said tilt carriage including means adapted to guide a cake of ice through said primary grating when said primary grating is substantially horizontal, said tilt carriage also including receiving means adapted to receive the ice mass after the cake of ice has been cleaved by the primary grating, said receiving means also adapted to guide the ice mass through the secondary grating when the secondary grating is substantially horizontal, pivot means having an axis parallel to both of said gratings and joined to the tilt carriage, a supporting frame carrying said pivot means for pivotal movement about a horizontal axis, releasable engaging means carried by the tilt carriage and the supporting frame and positioned away from the axis of the pivot means, said engaging means being releasable to allow tilting movement of the tilt carriage on said supporting frame, said engaging means being so positioned relative to one another that their engagement takes place when the tilt carriage is in position to present the primary grating in substantially horizontal position, an extension piece adapted to extend above the primary grating, said extension piece having a lateral contacting portion extending therefrom,

means carried by the tilt carriage to guide the extension piece in a path perpendicular to the plane of the primary grating and out of line with the primary grating, said contacting piece being adapted to extend over the primary grating and to contact and transmit downward pressure from said extension piece downward against a cake of ice resting on the primary grating, means to urge the extension piece downward, and tripping means carried by the extension piece to release said engaging means by exerting downward pressure upon said engaging means, said releasing means being positioned to release the engaging means upon lowering of said lateral contacting portion against the primary grating, whereby the tilt carriage is free to tilt.

4. In an ice cubing machine of the cleaving-by-melting type, a tilt carriage having cleaving edges spaced to mark out two planes substantially perpendicular to one another and thereby forming a primary grating and a secondary grating, means for heating said gratings, said tilt carriage including means adapted to guide a cake of ice through said primary grating when said primary grating is substantially horizontal, said tilt carriage also including receiving means adapted to receive the ice mass after the cake of ice has been cleaved by the primary grating, said receiving means being also adapted to guide the ice mass through the secondary grating when the secondary grating is substantially horizontal, pivot means having an axis parallel to both of said gratings and joined to the tilt carriage, a supporting frame carrying said pivot means for pivotal movement about a horizontal axis, said pivot means being so placed that the tilt carriage and its ice contents will tend to turn on said pivot means to that position wherein the tilt carriage has its secondary grating substantially horizontal, releasable engaging means carried by the tilt carriage and the supporting frame and positioned away from the axis of the pivot means, said engaging means being releasable to allow tilting movement of the tilt carriage on said supporting frame, said engaging means being so positioned relative to one another that their engagement takes place when the tilt carriage is in position to present the primary grating in substantially horizontal position, a rod having a lateral branch at one end, a tubular guide carried by the tilt carriage to guide said rod in a path perpendicular to the plane of the primary grating and out of line with the primary grating, said branch being adapted to extend over the primary grating and transmit downward pressure from said rod downward against a cake of ice resting on the primary grating, a spring so tensioned between said rod and the tilt carriage as to urge the rod downward, a trigger arm carried by the lower portion of said rod and adapted to release said engaging means by exerting downward pressure on a part of said engaging means, said trigger arm being positioned to release the engaging means upon lowering of said lateral branch against the primary grating, whereby the tilt carriage is free to tilt, means carried by said rod and the tubular guide adapted to engage each other when said rod is raised to non-releasing position and turned to hold said branch away from the primary grating, whereby the tilt carriage will remain locked in position and said lateral branch will be held out of the way to facilitate place-

ment of a large block of ice on the primary grating.

5. An ice cubing machine of the cleaving-by-melting type comprising in primary position two flat parallel side walls, a flat rear wall, a flat bottom, said rear wall and said bottom having means joining said side walls and positioned at right angles to the side walls and to each other, primary cleaving edges carried by the side walls fixedly above and parallel to the bottom, secondary cleaving edges carried by the side walls fixedly in front of and parallel to the rear wall, the side walls and rear wall and bottom and cleaving edges forming a tilt carriage, each of said cleaving edges having a conduit along its length adapted to carry a flow of heating fluid, an inlet pipe and an outlet pipe to pass heating fluid through said channels, a supporting frame, said tilt carriage being rotatively supported by the supporting frame so that the side walls are perpendicular to the axis of rotation, an extension piece adapted to extend above the primary cleaving edges, said extension piece having fixed thereto a lateral contacting portion extending therefrom, guiding means carried by the tilt carriage adapted to receive and guide the extension piece in a path perpendicular to the primary cleaving edges and out of line with the primary cleaving edges, said contacting piece being adapted to extend over the primary cleaving edges and to contact and transmit downward pressure from said extension piece downward against a cake of ice resting on the primary cleaving edges, said contacting piece also being swingable away from said contacting position means to urge the extension piece downward, means carried by the tilt carriage and the supporting frame to releasably hold the tilt carriage in said primary position wherein the rear wall is predominately vertical and wherein the rear wall and the bottom form a dihedral angle the two planes of which converge downwardly toward the apex, means carried by the extension piece to release said holding means, said axis of rotation of the tilt carriage being so positioned that the tilt carriage is normally overbalanced and urged into secondary position, said secondary position being that position wherein the bottom is predominately vertical and the rear wall is predominately horizontal, and means to prevent the tilt carriage from rotating past the secondary position upon release of said holding means.

6. In a machine having heated edges for simultaneously cutting through a block of ice, a plurality of tubes, said tubes being disposed to approximate a substantially horizontal plane surface and forming a grating to receive and support a block of ice for a cleaving operation, each of said tubes presenting edges of narrow width across the path of the ice blocks when melting through said grating, said tubes having inlet and outlet connections providing a flow of heating fluid through said tubes, means for providing a constant downward pressure on top of a block of ice to be placed on said grating, said downward pressure being exerted principally on that portion of the ice block nearest the outlet ends of the tubes, whereby the colder, outlet ends of the tubes will have firmer contact with the ice to speed the rate of melting there and tend to equalize such rate with the rate of melting at the warmer inlet ends of the tubes.

MIGIEL J. ULINE.
